(57) **CLAIM**

The ornamental design for an air drying stand, as shown and described.

DESCRIPTION

FIG. 1 is a front isometric view of an air drying stand showing one embodiment of my new design.

FIG. 2 is a bottom isometric view thereof.

FIG. 3 is a top plan view thereof.

FIG. 4 is a bottom plan view thereof.

FIG. 5 is a front elevational view thereof.

FIG. 6 is a rear elevational view thereof.

FIG. 7 is a left side elevational view thereof; and, FIG. 8 is a right side elevational view thereof.

Portions of the air drying stand are shown broken away to indicate that they have no particular length beyond what is shown.

The broken lines depict portions of the article that form no part of the claimed design.
